CLAIM

I claim the ornamental design for a poster clasp, as shown and described.

DESCRIPTION

FIG. 1 is a perspective view of a poster clasp according to an embodiment of the invention.

FIG. 2 is a front elevational view of the poster clasp depicted in FIG. 1, shown cut away for the ease of illustration;

FIG. 3 is a side elevational view of the poster clasp depicted in FIG. 1, shown cut away for the ease of illustration;

FIG. 4 is a rear elevational view of the poster clasp depicted in FIG. 1, shown cut away for the ease of illustration;

FIG. 5 is a top elevational view of the poster clasp depicted in FIG. 1, shown cut away for the ease of illustration; and,

FIG. 6 is a bottom elevational view of the poster clasp depicted in FIG. 1, shown cut away for the ease of illustration. Items shown in the broken lines are for illustrative purposes only and form no part of the claimed invention.
